UNITED STATES PATENT OFFICE.

JAMES FIDDES AND JOHN FORDYCE WATT, OF ABERDEEN, SCOTLAND, ASSIGNEES TO THE EXPANSION SPRINKLER SYNDICATE, LIMITED, OF ABERDEEN, SCOTLAND.

AUTOMATIC TRANSMITTER FOR FIRE-ALARM AND SPRINKLER SYSTEMS.

No. 877,067.

Specification of Letters Patent.

Patented Jan. 21, 1908.

Application filed October 26, 1906. Serial No. 340,641.

To all whom it may concern:

Be it known that we, JAMES FIDDES and JOHN FORDYCE WATT, subjects of the King of the United Kingdom of Great Britain and 5 Ireland, and residing at Aberdeen, Scotland, have invented a certain new and useful Improvement in Automatic Transmitters for Fire-Alarm and Sprinkler Systems, of which the following is a specification.

- 10 This invention relates to fire alarm and sprinkler systems and has for its object to provide an instrument for the purpose of automatically communicating with a fire brigade station or other point and indicating 15 when an automatic sprinkler or fire alarm in a building has been brought into action.

The improved instrument is illustrated in the accompanying drawings in which

Figures 1 and 2 are vertical sections the 20 first showing the instrument in the normal position and the second showing it when brought into action on the fluid pressure of a sprinkler or alarm system being released on the occasion of fire or abnormal rise of temperature in the building in which the system is installed.

As shown, the instrument comprises a metallic vessel A containing mercury or other liquid of high density capable of floating a heavy metal or other weight, said vessel 30 having a connection at a to the compressed air or water piping of the sprinkler or fire alarm system.

From a recess or pocket A¹ in the lower 35 end of the vessel A a tube B extends up into a cylinder C in which is fitted loosely a metal or other float D at whose upper end is a spindle E fitted with collars e, the said spindle extending through an opening in the 40 cover C¹ of the cylinder C. On a bracket F on the cover C¹ are pivoted the contact arms or levers G G¹ insulated from each other, the one arm G being adjustable by a screw g but practically stationary and the other arm G¹ 45 having a nose piece g¹ projecting into the path of movement of the collars e on the spindle and being adapted to tilt on its pivot so as to make contact with the other arm or lever G.

50 In the operation of the apparatus the liquid in the vessel A is forced by the pressure of the water or air in a sprinkler system or by that of the air in an automatic fire

alarm system up through the tube B into the cylinder C so that the metal float D rises to 55 the upper end as indicated at Fig. 1. On the air or water pressure being released owing to the fire alarm or sprinkler being brought into action the liquid in the cylinder C flows back into the vessel A, the metal weight following 60 the liquid. As the weight falls the collars e on the spindle E in succession bear on the nose g¹ of the contact maker G¹ so as to tilt it and make contact with G whereby an electric circuit is closed during the time the collar is passing the contact maker. During the time taken for the collar to pass the contact maker a receiver of well known type, such as the Siemens-Morse receiver, at the fire brigade station or other point makes a 70 dash on a strip of paper, the length of the dash corresponding with the breadth of the collar e, while the distance between each collar is represented by a space on the strip of paper passing through the receiver. The 75 number and length of the dashes made depends on the number and width of the collars.

By the arrangement described the use of 80 clock-work in an instrument for transmitting a fire call in an automatic fire alarm or sprinkler system is eliminated.

Having now described our invention what 85 we claim and desire to secure by Letters Patent of the United States is;—

1. In a fire alarm or sprinkler system, a transmitting instrument comprising a vessel, containing liquid, for communication with a pressure duct of an alarm or sprinkler system a float which rises and falls with said liquid, when the level of such is effected by the pressure in the duct, and a stationary electrical contact lever and a pivotal electrical contact lever and means connected with the float for moving the pivotal electrical contact lever on the descent of said float.

2. In a fire alarm or sprinkler system, a transmitting instrument comprising a vessel, containing liquid of high density, for communication with a duct of an alarm or sprinkler system, a cylinder a tube extending from said cylinder and having one end immersed in the liquid of high density, a float in said cylinder, a spindle secured to said float and fitted with a succession of collars, and electrical contact levers which are normally sepa-

rated but which are successively brought into contact by the collars on the descending float.

3. In a fire alarm or sprinkler system, a transmitting instrument comprising a chamber which is adapted for communication with a pressure duct of an alarm or sprinkler system, a second chamber, means connecting said chamber and permitting liquid to pass 10 back and forth from one chamber to the other, a float in the said second chamber, normally separated electrical contact levers,

and means connected with the float for bringing said levers into contact upon descent of said float. 15

In testimony whereof we have signed our names to this specification in the presence of two subscribing witnesses.

JAMES FIDDES.
JOHN FORDYCE WATT.
